UNITED STATES PATENT OFFICE.

THOMAS A. WATSON, OF EVERETT, MASSACHUSETTS.

VIBRATING SURFACE FOR SOUND-TRANSMISSION.

SPECIFICATION forming part of Letters Patent No. 232,862, dated October 5, 1880.

Application filed April 12, 1880. (No model.)

To all whom it may concern:

Be it known that I, THOMAS A. WATSON, of Everett, county of Middlesex, State of Massachusetts, have invented an Improvement in Vibrating Surfaces for Sound-Transmission, of which the following description, in connection with the accompanying drawing, is a specification.

My invention relates to telephones, and has for its object to increase the amplitude of the vibrations of the armature of the transmitting-telephone or of any instrument used for transmission, as a carbon transmitter. To accomplish this result I make use of fluid or gaseous pressure, confining the fluid or gas in a chamber or reservoir of rigid material, having a part of its surface of a considerable area removed and the opening closed by a flexible diaphragm suitable to be vibrated by the usual sound-vibrations, and having also a much smaller opening, which may be fitted with a piston or closed by another elastic or flexible diaphragm. The piston or smaller diaphragm may be or sustain the armature of a magnet, or they may act upon the carbon of a microphone-transmitter, or act in any other usual way to cause electric pulsations; and it will be understood that the amplitude of the vibrations of the small surface will be as many times greater than those of the large surface as its area is less, and the electric effect to cause transmission of sound will be proportionally increased or multiplied.

The drawing shows, in longitudinal section, sufficient portion of a telephone to illustrate my invention.

The reservoir *a*, of material sufficiently rigid not to yield under the pressure of the contained fluid or gas, is shown as funnel-shaped and screw-threaded on its outside at the large open end, where a diaphragm, *b*, which may be of the kind generally employed, may be secured by screwing on a mouth-piece, *c*, of usual construction. The edge of the reservoir is made smooth and the diaphragm carefully fitted thereto and provided with packing, or with a coating of lead or other suitable material, if necessary, in order to make a perfectly tight joint.

The smaller opening is shown as provided with a tight-fitting piston, *d*, which may carry

at its outer end a piece of soft iron, as the armature of the magnet *e*, or may be arranged to press against a carbon point, to cause by its vibration fluctuations in an electric current induced by the magnet or passing through the said carbon.

The plunger *d* is shown as connected with a diaphragm, *d'*, which in this case merely acts as a spring to give resilience to the movement of the piston *d*.

Any kind of liquid or gaseous fluid may be used in the chamber *a*; but I find in practice that air, water, alcohol, and glycerine each give excellent results, and it is sometimes desirable to use a flexible diaphragm as the smaller vibratory surface instead of the piston *b*.

It is obvious that this invention may be applied to any apparatus in which the sound-vibrations of the air are to set a plate or diaphragm in vibration—as, for example, in a phonograph—and that the plane of the smaller surface may be placed at any desired angle to that of the larger surface.

It may sometimes be desirable to use this apparatus in connection with a receiving or speaking instrument, the larger plate then being set in vibration by magnetic action or mechanically, and the smaller one giving out sound. If it should be desired, more than one small surface may be set in vibration from the vibrations of a larger surface through the medium of fluid-pressure.

I claim—

1. That improvement in the art or method of transmitting or reproducing sound-vibrations which consists in increasing the amplitude of said vibrations by means of the pressure of a confined fluid, substantially as described.

2. In an apparatus for transmitting sound-vibrations, a chamber or reservoir to contain a fluid, provided with two flexible or movable surfaces of different area, whereby the vibratory movement of the larger surface imparts, through the medium of the fluid, a similar vibratory movement to the smaller surface, all the movements of the smaller surface being proportional to those of the larger surface, but of increased amplitude, thereby giving more powerful effects, substantially as described.

3. In a telephonic apparatus, a fluid-cham-

ber having a large opening, and a telephone diaphragm and mouth-piece tightly fitted thereon, and a smaller opening and a movable surface to close the same, whereby vibrations of the larger diaphragm transmit, through the fluid in the chamber, similar vibrations, but of greater amplitude, to the smaller surface, substantially as described.

In testimony whereof I have signed my name to this specification in the presence of 10 two subscribing witnesses.

THOMAS A. WATSON.
